UNITED STATES PATENT OFFICE

148,413

DESIGN FOR A LACE OR THE LIKE

Abraham Gottlieb, New York, N. Y.

Application December 20, 1946, Serial No. 135,650

Term of patent 3½ years

(Cl. D47—6)

To all whom it may concern:

Be it known that I, Abraham Gottlieb, a citizen of the United States, residing in the Borough of Manhattan, city, county, and State of New York, have invented a new, original, and ornamental Design for a Lace or the Like, of which the following is a specification, reference being had to the accompanying drawing, forming part thereof.

On the drawing, the figure is a plan view of a lace or the like, showing my new design.

The unit repeats beyond the dot-and-dash lines in regular succession.

While the design disclosed herein is shown applied to a lace, it obviously may be applied to other materials, as, for example, other textile materials.

I claim:

The ornamental design for a lace or the like, substantially as shown and described.

ABRAHAM GOTTLIEB.
